UNITED STATES PATENT OFFICE

JOHN B. OLSON, OF FORT ATKINSON, WISCONSIN, ASSIGNOR TO JAMES MANUFACTURING COMPANY, OF FORT ATKINSON, WISCONSIN

MANGER GUARD

Application filed October 17, 1927. Serial No. 226,608.

This invention relates to improvements in manger guards, including partitioning members for subdividing mangers in general correspondence with the stall partitions, and also including guard rails such as are employed to protect the upper margin of the manger wall and to prevent material from being thrown over such wall by the animals.

Movable division guards or partitioning members have heretofore been made and connected with stanchion frames in such a manner that the guards or partitions can be lifted and supported in a raised position to facilitate cleaning the manger. Partition members or guards of this general type are disclosed in Letters Patent of the United States to John James, No. 1,186,514, dated June 6, 1916, and the object of this invention is to improve such guards, to provide means for connecting them in groups or pairs to a manger guard rail, and to provide means for connecting the latter with stanchion frame posts in such a manner as to furnish additional protection to the partition members, allowing the vertical dimensions of the partition members to be reduced to a minimum and allowing partition members and guard rails or guard rail members to be raised and supported in a raised position pending a stall cleaning operation, whereby the guard rails, their supports and partition members may be out of the way and cleaning devices operated from end to end of the manger without obstruction.

In the drawings:

Fig. 1 is a plan view of a stanchion frame and manger equipped with my invention.

Figure 2 is a transverse sectional view of the manger and stanchion frame showing one of the partition members associated with the guard rail and with dotted lines indicating the movable parts as they appear when raised and secured in a position of non-use.

Like parts are identified by the same reference characters in both views.

The partition members 10 are each provided with an arm 11 extending upwardly and rearwardly from their rear margins and pivoted at 12 to a bracket 13 which is clamped to a stanchion frame post 14. The posts of the stanchion frame are, of course, located in line

with the stall partitions and a guard 10 will be associated with each such partition to divide the portion of the manger in front of one stall from that in front of the adjacent stall. The bottom wall of the partition 10 will be contoured in conformity with the bottom portion of the manger wall 16 which will ordinarily be formed of concrete. A link bar 17 is secured to the front end portion of the partition member 10 by a pivot pin 18, the bar 17 being preferably forked so as to embrace opposite sides of the partition, both forked arms being connected by the pivot pin 18. The upper end of this link bar 17 is pivoted at 20 to a clamping bracket 21 which engages the guard rail or guard rail section 22. Each of the brackets 21 is connected by a rod 24 to a bracket 25 which is clamped to the stanchion post 14, the rod 24 being pivoted to the bracket 25 at 27. Each guard rail member is connected by at least two rods 24 with brackets 25 clamped to frame posts 14. Therefore, at least two partition guards 10 will be associated with each guard rail member and connected thereto by links 17. The length of the guard rail member will, of course, determine the number of partition members 10 to be connected therewith and the weight of the parts will ordinarily determine the length of the guard rail member and the number of associated partition guards which it will be convenient to raise in one operation.

The links 11 and 17 are so proportioned to the dimensions of the partition member 10 and the partition rod 24 as to allow the partition member 10 to occupy the position indicated by dotted lines in Figure 2 when the parts are raised to the position of non-use. In this position, the parts may be held by latch members 30, pivoted to the link bars 11 at 31 and adapted to drop by gravity into engagement with the upper surface of the bracket 13 when the movable parts are raised to the position of non-use. When it is desired to lower these parts, a slight push against them, tending to swing the rod 24 toward the stall frame will release these latches and allow the partition guards and associated guard rail member to be lowered to normal position of use.

The rod 24 is adapted to constitute an adjustable element of a stall partition since it extends over the manger in front of the partition bar 31. The connections with the manger partition 10 are so proportioned in length that when the rod is raised to a position of non-use, the manger partition will extend vertically over the manger space and serve as a stall partition member in place of the rod 24. The manger partition preferably has a buffer plate 32 to prevent its front margin from damage if lowered too rapidly or dropped into normal position of use.

From the above description it will be apparent that an attendant may raise a number of manger partitions by grasping and raising the guard rail 22. The various parts of the swinging structure will assume the position shown in dotted lines in Figure 2, as the guard rail assumes a position parallel to and adjacent the stanchion posts, a position which it assumes after traveling through an arc governed by the arms 24 pivoted at 27, as above indicated. The attendant is enabled to place the partition members at a considerable height above the manger, thereby completely removing them as obstructions to the cleaning of the manger.

I claim:

1. The combination with a manger, of a support at one side thereof, a guard rail at the opposite side thereof having a supporting arm pivoted to the support, and a manger partition member linked to the guard rail and pivotally connected with its support.

2. The combination with a manger provided with manger partitions, partition supports along one side of the manger having pivoted arms secured to said partitions, a manger guard extending along the opposite side of the manger and connected with said partitions, and arms on said manger guard extending across the manger and pivotally supported for swinging upward movement concurrently with the movement of the partitions about their pivoted supports.

3. The combination with a manger and stanchion frame, of a set of manger partitions, a guard rail linked thereto, arms connected with the guard rail and pivoted to the stanchion frame, and other arms secured to the partitions and pivoted to the stanchion frame and adapted to allow the guard rail and partitions to be simultaneously raised to a position of non-use unobstructive of the manger space.

4. The combination with a manger and stanchion frame, of a set of manger partitions, a guard rail linked thereto, arms connected with the guard rail and pivoted to the stanchion frame, other arms secured to the partitions and pivoted to the stanchion frame and adapted to allow the guard rail and partitions to be simultaneously raised to a position of non-use unobstructive of the manger

space, and a latch adapted to hold the guard rail and partitions in said raised position.

5. The combination with a manger and stanchion frame, of a set of manger partitions pivotally connected with the stanchion frame, superposed partition bars also pivotally connected with the stanchion frame, one above each manger partition, said partition bars being connected with each other at the side of the manger opposite that occupied by the stanchion frame, and linkage connecting the manger partitions thereto.

6. The combination with a manger, of a movable manger partition member, a rod substantially in the plane of the partition member and extending over the manger space at a materially higher level, means for pivotally supporting one end of the rod, and a link connection between the rod and partition member.

7. The combination with a manger, of a movable manger partition member, a rod substantially in the plane of the partition member and extending over the manger space at a materially higher level, means for pivotally supporting one end of the rod, and a connection between the rod and partition member, said rod being also provided with a manger guard extending transversely of the rod at the side of the manger occupied by the animal and spaced inwardly from the upper margin of the manger.

8. A stanchion frame, an adjustable manger guard rail provided with a pivotal connection to the frame, a manger partition pivotally secured to the frame at a point offset from the pivotal connection of the guard rail, and a link between the guard rail and the partition.

9. A stanchion frame, an adjustable manger guard rail provided with a pivotal connection to the frame, a manger partition pivotally secured to the frame at a point offset from the pivotal connection of the guard rail, and a link pivotally secured to the stanchion frame and to the guard rail and the partition.

10. A stanchion frame, a manger provided with movable partitions, a link between the stanchion frame and each partition providing pivotal mounting for the movement of the partition in a vertical plane, a manger rail normal to the partitions and pivotally supported from the frame and a bar pivotally secured to the rail and to each partition.

JOHN B. OLSON.
